W. E. CLIFTON

DIAPHRAGM FOR SOUND RECORDING AND SOUND REPRODUCING INSTRUMENTS

Filed Nov. 12, 1921

UNITED STATES PATENT OFFICE.

WILLIAM ERNEST CLIFTON, OF NOTTINGHAM, ENGLAND, ASSIGNOR TO CLIFTOPHONE LIMITED, OF LONDON, ENGLAND.

DIAPHRAGM FOR SOUND-RECORDING AND SOUND-REPRODUCING INSTRUMENTS.

Application filed November 12, 1921. Serial No. 514,592.

To all whom it may concern:

Be it known that I, WILLIAM ERNEST CLIFTON, a subject of the King of England, residing in Nottingham, England, have invented certain new and useful Improvements in Diaphragms for Sound-Recording and Sound-Reproducing Instruments, of which the following is a specification.

This invention consists in improvements in or relating to diaphragms for sound-reproducing and sound-recording instruments, for example diaphragms for use with gramophones and like apparatus. The object of the invention is to provide an improved means of connection between the inner end of the stylus-bar and the diaphragm.

Hitherto the inner end of the stylus-bar, the outer end of which is fitted with the needle, has generally been flattened and secured to the diaphragm by means of a small nut and bolt passing through the flattened end of the stylus-bar and the material of the diaphragm in a direction substantially normal to the plane of the diaphragm. It has been found in practice that after the diaphragm has been in use for some time a certain jarring noise often becomes apparent which is now believed to be due to a loosening of the connection between the stylus-bar and the diaphragm.

According to the present invention there is provided, on one face of the diaphragm, a lug or lugs which project from the diaphragm at right-angles to the surface thereof and to which the stylus-bar is, or is to be, connected. Conveniently a strip or strips of material are secured to one face of the diaphragm with a portion of the strip or of each strip projecting through an orifice in the diaphragm so as to extend at right-angles to the surface of the latter on the opposite side of it from that to which the strip or strips are secured, the projecting portion or portions affording the lug or lugs aforesaid.

According to another feature of the invention a metallic or other "hard" member is provided in contact with, or integral with, the inner end of the stylus-bar and extending towards the diaphragm up to or beyond the plane of the outer face of the latter, that is to say that face of the latter which is adjacent to the stylus-bar.

By the term "hard" as applied to the

above-named member is meant a characteristic of the material of the member which is hard in comparison with a substance like the fibre of the lugs to be described herein-after. "Hard" does not necessarily mean metallic hardness as it may be hard in the sense that box-wood or lignum vitæ, for example, are hard.

Conveniently the hard member extends completely through the diaphragm with its end exposed to the atmosphere beyond the inner face of the diaphragm, that is to say the atmosphere within the sound-box.

The invention will be more clearly understood from the following description given by way of example only, of a preferred manner of carrying the invention into effect and read in conjunction with the accompanying drawings, in which—

Figure 1 shows a front elevation of a part of the diaphragm and the stylus-bar;

Figure 2 is a section on an enlarged scale through a part of the diaphragm only on the line 2—2 of Figure 1;

Figures 3 and 4 are views similar respectively to Figures 1 and 2 of a modified form of diaphragm;

Figure 5 is a view similar to Figure 1 of a further modification; and

Figures 6-9 illustrate, on an exaggerated scale, sections through a diaphragm and stylus-bar connection of further modified constructions according to the present invention.

Like reference numerals indicate like parts in the several figures of the drawings.

In Figures 1 and 2 a simple diaphragm is illustrated as comprising a disc 1 of any preferred yielding material, such as is suitable for diaphragms of this nature. The diaphragm 1 is as usual, secured within a sound-box casing indicated at 2. To the back or inner surface of the disc 1 are secured two strips 3 of material such as fibre or celluloid, the adjacent extremities of which project at right-angles at 4 through an orifice in the material of the diaphragm so as to extend beyond its front or outer surface. The parts 4 constitute two lugs between which the inner end of the stylus-bar 5 is received and to which it is secured by means of a transverse pin 6 having at one end a head 7, and at the other a nut 8 cooperating with the screw-threaded extremity of the pin 6. By means of the nut 8 the

lugs in the stylus-bar end can be clamped tightly together.

In Figures 3 and 4 the connection between the inner end of the stylus-bar and the diaphragm is effected through the medium of the strips 3 having lugs 4 which project through an orifice in the diaphragm. In this illustrated application of the invention, however, the diaphragm 1 is stiffened by additional strips 9 and 10 applied to the same sides of it with their inner extremities abutting at the centre line of the disc 1. Over the strips 9 and 10 is secured a cover 11 of celluloid which completely encloses the strip.

15 The strip 3 is secured in this case over the cover 11 as shown clearly in Figure 4.

It will be seen that the diaphragm illustrated in Figures 3 and 4 is of the construction such as is described in my co-pending application Ser. No. 514,591, filed Nov. 12, 1921, the invention is equally applicable to diaphragms constructed according to my prior application Ser. No. 479,879 or in fact to any type of diaphragm employed in apparatus of the class to which the present invention relates.

In place of the two separate strips 3 as illustrated a single strip of material having a looped portion folded back on itself to take the place of lugs 4 could be employed, with the inner ends of the stylus-bar secured either between the two laps of the loop or in contact with the outer surface of one of the laps of the loop.

35 Instead of forming the inner end of the stylus-bar with a flattened portion as illustrated in Figures 1-4 to be received between or in contact with lugs such as 4, the inner extremity of the stylus-bar can, as shown in Figure 5, be bifurcated so as to receive between the two arms thus provided, the lugs such as 4, the two arms of the stylus ends and the lugs being secured together by a transverse pin similar to that illustrated.

40 It is found that with the present construction the tendency to loosening at the connection of the stylus-bar with the diaphragm is largely, if not completely eliminated, and the jarring noise referred to as appertaining to constructions at present generally in use is also largely, if not completely, eliminated.

45 In the construction illustrated it is found that the strips 3 or their equivalent, owing to the central division constituted by the formation of the lugs, will impart to the stiffening strips 9 and 10 a tendency to bend or flex along a diametral line crossing centrally through the stiffening strips parallel with the stylus-bar.

50 It is obvious that while the invention may be applied to any preferred form of diaphragm it is not necessary that the lugs 4 should be constituted solely in the manner illustrated. For example, a lug or lugs sim-

ilar to the lugs 4 can be constituted by any projection however formed either as an additional piece applied to the diaphragm or by a portion of the material of the diaphragm which is punched up to the required form. Also, instead of using the small nut and bolt 7, 8 a single screw may be employed. Between the end of the stylus-bar and the lugs 4 may be applied any desired form of adhesive paste which may be additional to the transverse screw securing the parts together, or in some instances, if the paste is sufficiently adhesive, it may be employed as the sole means of connecting the stylus-bar with the lug or lugs such as 4.

55 In Figure 6 the diaphragm 1 has preferably secured to it, as before, strips such as 9 and 10, a cover 11 and other strips 3 formed with lugs 4 projecting from the diaphragm from back to front. The inner end of the stylus-bar, that is the end connected to the lugs 4, is of such length as to pass between them so that its inner extremity terminates approximately flush with the back of the strips 3 and is exposed to the atmosphere within the sound-box casing. The stylus-bar and lugs are secured by means of bolts and nuts 7 and 8 or their equivalent, as in the previously described constructions.

60 In Figure 7 a similar construction is shown with the exception that the extremity of the stylus-bar is not tapered.

In Figure 8 the inner end of the stylus-bar does not project completely through between the lugs but an additional hard member 12, abutting the end of the stylus-bar, is held between the lugs in close mechanical contact with the stylus-bar and serves as a virtual extension of it.

65 In Figure 9 one of the lugs 4 is shown as shorter than the other and the end of the stylus-bar abuts the shorter end. An additional hard member 12 is clamped between the longer lug and the stylus-bar and preferably extends to a position through and between the lugs 4 to be exposed within the sound-box casing.

70 It is not necessary that the stylus-bar or the members such as 12 be extended completely through the diaphragm as the invention contemplates a hard member extending either up to or beyond the plane of the outer face of the diaphragm and formed either as an integral extension of the stylus-bar, as illustrated in Figures 6 and 7, or as a separate member. For example, in the construction illustrated in Figure 8 the member 12 may be dispensed with when the stylus-bar will terminate approximately on a plane containing the front or outer face of the diaphragm. The dimensions of the parts will be such that the lugs 4 are held tightly together.

75 80 85 90 95 100 105 110 115 120 125 130 In any of the constructions the hard mem-

ber may be tapered in the manner in which the stylus-bar itself is tapered in Figure 6. Preferably the tapering is from a thickness of approximately ten to twelve-thousandths 5 of an inch down to from three to four-thousandths of an inch.

When the hard member is non-tapered it is found that a strip of metal such as tinned iron of from three to four-thousandths of an 10 inch thick and approximately one-eighth of an inch in width will give a successful result with, for example, a diaphragm of two inches diameter and say ten-thousandths of an inch thick.

15 In place of providing an additional hard member this may be constituted by a metallic coating applied, for example, mechanically or by electro-deposition as a thin layer to the inner surface of one or each of the lugs 4.

20 What I claim as my invention and desire to secure by Letters Patent is:—

1. In a diaphragm of flexible and substantially non-resilient material for sound-recording and sound-reproducing instruments, 25 at least one stiffening element superimposed on said diaphragm in the region of its central portion and secured thereto, two lugs extending from the outer face of the diaphragm and at right angles thereto and 30 each constituting part of a strip which extends transversely over the aforesaid stiffening element, and means to secure the inner end of a stylus-bar between said lugs, substantially as described.

35 2. In a sound-box of the type specified, the combination of a diaphragm, articulating means projecting from the outer face of the diaphragm at right angles thereto, a stylus-bar having its inner end connected by said 40 articulating means to the diaphragm, and a "hard" member additional to the articulating means extending at one end towards the diaphragm at least up to the plane of the outer face thereof and at the other end 45 forming a close-contact connection with the inner end of the stylus-bar, substantially as described.

3. In a sound-box of the type specified, the combination of a diaphragm, articulating 50 means projecting from the outer face of the diaphragm at right angles thereto, a stylus-bar having its inner end connected by said articulating means to the diaphragm, and a "hard" member additional to the articulating means and extending at one end 55 completely through the diaphragm, whereby said end is exposed to the atmosphere beyond the inner face of said diaphragm, and at the other end forming a close-contact connection with the inner end of the stylus-bar, substantially as described.

4. In a sound-box of the type specified,

the combination of a diaphragm, articulating means projecting from the outer face of the diaphragm at right angles thereto, a 65 stylus-bar having its inner end connected by said articulating means to the diaphragm, and a "hard" member additional to the articulating means and extending at one end at least up to the plane of the outer face of 70 the diaphragm, said end being exposed to the atmosphere beyond the inner face of said diaphragm, and at the other end forming a close-contact connection with the inner end of the stylus-bar, said "hard" member being 75 in the form of a flat strip whose dimension in a plane parallel with the length of the stylus-bar and normal to the plane of the diaphragm is large in comparison with the thickness thereof, substantially as described. 80

5. In a sound-box of the type specified, the combination of a diaphragm, articulating means projecting from the outer face of the diaphragm at right angles thereto, a stylus-bar having its inner end connected by said 85 articulating means to the diaphragm, and a "hard" member additional to the articulating means and extending at one end at least up to the plane of the outer face of the diaphragm, said end being exposed to the atmosphere beyond the inner face of said diaphragm, and at the other end forming a close-contact connection with the inner end of the stylus-bar, said "hard" member being wedge-shaped and tapering towards that 90 extremity of it which approaches the diaphragm, substantially as described.

6. In a sound-box of the type specified, the combination of a diaphragm, two lugs extending from the outer face of the diaphragm at right angles thereto, a stylus-bar, the inner end of which is secured between said lugs, and a "hard" member disposed between said lugs and extending at one end at least up to the plane of the outer face of 100 the diaphragm, and at the other end forming a close-contact connection with the inner end of the stylus-bar, substantially as described.

7. In a sound-box of the type specified, a 110 diaphragm having an aperture in the region of its centre, a stylus-bar having its inner end extending completely through said aperture, an articulating member one end of which is parallel with and secured to the 115 inner face of the diaphragm and the other end of which extends through the aforesaid diaphragm aperture at right angles to and beyond the outer face of the diaphragm, and means for securing the free end of the articulating member to the stylus-bar, substantially as described. 120

In testimony whereof I affix my signature.

WILLIAM ERNEST CLIFTON,
